UNITED STATES PATENT OFFICE.

JOHN O'BRIEN, OF NEW HAVEN, CONNECTICUT.

WHIFFLETREE-COUPING.

SPECIFICATION forming part of Letters Patent No. 249,252, dated November 8, 1881.

Application filed July 26, 1881. (No model.)

To all whom it may concern:

Be it known that I, JOHN O'BRIEN, a citizen of the United States, residing at New Haven, in the county of New Haven and State of Connecticut, have invented certain new and useful Improvements in Whiffletrees and Cross-Bar Couplings; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The device consists of two plates having at each end perforated lugs, by which they are secured, one to the under side of the cross-bar and the other to the upper face of the whiffletree. Each plate has a central boss or projection bearing upon one another when the coupling is in position. On the inner side of one plate is an enlarged central recess, into which loosely fits a disk having pins on one of its sides, said pins fitting into corresponding openings in the other plate, thereby holding said plates together. An orifice passes centrally through the plates, disk, and the whiffletree or bars to be coupled, and receives a bolt having on one end a screw-thread, on which works a nut to hold the bars and parts together.

In the drawings, Figure 1 shows a side elevation of a pair of bars having my improved coupling applied thereto. Fig. 2 is a vertical longitudinal section of the same. Fig. 3 is a top view of the coupling device.

A represents the upper, and B the lower, bar to be coupled.

C and D represent two plates, having at their ends flanges or lugs a, perforated at b, through which screws, bolts, or other suitable retaining devices, c, are passed to secure said plates to the bars. Each plate has a central boss or projection, E, which affords a bearing-surface upon which the bars A, B may turn. The plate C has, as shown in Fig. 2, an enlarged central recess, d, within which fits loosely a disk, F. Both the recess d and the disk F gradually diminish in size circumferentially from top to bottom, and are of such a taper that the disk just fits the plate C loosely.

e e represent two or more pins, which are cast integrally with or rigidly secured to the smallest face of the disk F. These pins fit tightly within the orifices f f in the plate D, and serve to hold said disk securely to said plate.

A slot, g, passes centrally through the disk, the plates, and the bars. A bolt, h, passes through this slot g, and is held in position by a nut, i, to secure said parts together.

The mode of application and operation of the device is as follows: The plate D being secured to the upper face of the bar or whiffletree B, the disk is inserted within the recess d in the plate C. This plate is then secured by the screws c to the bar A. The two plates C D are then brought together at E, and the pins e forced within the orifices f. The screw-bolt h is then passed through the central orifice, g, the nut i screwed thereon, and the whole secured together. Each plate C D is rigidly secured to its respective bar. The disk F is rigidly secured by means of the pins e to the plate D, but is loose within the recessed plate C, so that on either bar turning it will have free rotary movement on said disk.

I am aware that whiffletree-couplings have been constructed of flanged plates, with central bosses or projections and a disk fitting within one of said plates, on which the other plate and its attached bar may rotate; but I am not aware that any disk corresponding to my disk F has yet been constructed with pins rigidly secured to or cast therewith. The advantages of such construction over those where the disk is secured in place by removable pins or screws are, that the device can be constructed more cheaply; no screw or pin holes have to be formed in the disk; the screw-threaded or other pins are dispensed with; there is no danger of my pins e becoming loose or lost; the disk can be more easily and speedily removed and the whiffletree uncoupled than where several screw-pins have first to be removed, and the coupling can also be more quickly applied in my case than would be possible where such removable pins are used.

Having thus described my invention, what I claim as new therein is—

1. The coupling herein described, consisting

of flanged plates C D, having central boss or projection, E, and the disk F, having rigid pins *e* projecting from one face thereof, substantially as and for the purpose set forth.

2. The combination of the plate C, having central boss, E, and recess *d*, the plate D, having central boss, E, and orifices *f g*, the centrally-perforated disk F, having rigid pins *e e* projecting from one face thereof, and adapted

to fit the orifices *f*, and the retaining device *h* ¹⁰ *i*, substantially as and for the purpose set forth.

In testimony whereof I affix my signature in presence of two witnesses.

JOHN O'BRIEN.
